UNITED STATES PATENT OFFICE

160,126

JUICE EXTRACTOR

Sol H. Rosenthal, Los Angeles, Calif.

Application August 5, 1949, Serial No. 4,319

Term of patent 14 years

(Cl. D89—1)

To all whom it may concern:

Be it known that I, Sol H. Rosenthal, a citizen of the United States, residing at Los Angeles, in the county of Los Angeles and State of California, have invented a new, original, and ornamental Design for a Juice Extractor, of which the following is a specification, reference being had to the accompanying drawing, forming part thereof.

In the drawing

Fig. 1 is a side elevational view of a juice extractor, showing my new design;

Fig. 2 is a front elevation;

Fig. 3 is a rear elevation; and

Fig. 4 is a top plan.

I claim:

The ornamental design for a juice extractor, as shown.

SOL H. ROSENTHAL.
